Primary Examiner — Janice Hallmark*Assistant Examiner* — Adedoyin Taiwo Odeyale(74) *Attorney, Agent, or Firm* — Jose Cherson Weissbrot(57) **CLAIM**

The ornamental design for a kitchen faucet sprayer head, as shown and described.

DESCRIPTION

FIG. 1 is a perspective view of a kitchen faucet sprayer head showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Broken lines in FIG. 2 and FIG. 7 illustrate portions of the kitchen faucet sprayer head that form no part of the claimed design.

1 Claim, 6 Drawing Sheets(56)
